UNITED STATES PATENT OFFICE

HARRY MILLER, OF NEWARK, NEW JERSEY

PARCEL RECEIVING CHUTE

Application filed January 19, 1932. Serial No. 587,505.

This invention relates to store fronts in general, and particularly to a chute which is located in the store and arranged as to receive a parcel from the outside.

One of the principal objects of my invention resides in the provision of an extremely simple and highly effective device which may be manufactured on a high production basis and be readily placed in its operative position within the inner portion of the store adjacent to an opening communicating with the outside or it may be instantly removed from its seated position and the opening sealed.

A further object of the invention resides in a locking member whereupon the chute or its corresponding sealing panel may be securely fastened from the inner side of the store.

A still further object of my invention is to provide means within the chute which will permit the ready passage of a parcel therethrough from the outer side of the store but which will automatically operate to prevent the retraction of the parcel through the chute.

For the attainment of the above and other objects as may hereinafter appear or be pointed out, I have illustrated an embodiment of my invention in the drawings, wherein:—

Figure 1 is a view in perspective illustrating a portion of a store front and showing my novel parcel receiving device as secured to the side frame of the door, portions thereof in dotted lines;

Figure 2 is a vertically longitudinal sectional view thereof, parts broken away;

Figure 3 is a rear elevation thereof, partially broken away and shown in section;

Figure 4 is a detail sectional view of a portion of the door similar to that shown in Figure 2 but illustrating the parcel receiving opening obstructed by the sealing panel, and

Figure 5 is a transverse sectional view taken on the line 5—5 of Figure 4.

My invention, in the form or embodiment shown in the drawings and briefly described, comprises a stationary supporting frame 10, a removably mounted parcel receiving chute 11, automatically operated means for preventing the removal of a parcel from the

chute 12, and locking means 13 for securely fastening the chute or its complementary sealing panel from their seated position.

The stationary supporting frame 10 which, in this instance, is illustrated as associated with a front door 14 of a store, is fitted within a substantially rectangular opening 15 and securely held in position by means of a plurality of suitably arranged bolts or other fastening means indicated as at 16. As clearly shown in Figures 2 and 5, the supporting frame 10 consists of an outer plate portion 17, and angularly disposed and inwardly extending portions 18. It will be noted that these inwardly projecting portions 18 extend slightly beyond the inner surface of the door frame 15 for a purpose to be hereinafter described.

A U-shaped frame 19 is located upon the inner side of the door frame 14 and is adapted to be securely held in position adjacent the opening 15 and its stationary supporting frame 10 by means of the bolts 16. A continuously formed groove 20 is provided in the side members 21 and in the bottom member 22 of the U-shaped frame 19. It will now be appreciated that the supporting frame 10 and its mating U-shaped member 19, by reason of their fastening means 16, will provide a substantially rigid support for the purpose of either effectually hanging the chute 11 or its removable panel.

The chute 11, which may be preferably formed of sheet aluminum or other desirable metal is formed with a vertically extending portion 23 and a slightly enlarged and curved upper portion 24. An outwardly extending and continuous flange 25 is integrally formed with the enlarged or upper portion 24 of the chute 11. This flange 25 may be either outwardly bent from the mouth of the chute or it may be formed in a substantially rectangular frame and secured thereto by welding or the like. The bead or flange 25 not only serves as a reenforcing means for that portion of the chute but provides a novel means whereby the chute is firmly supported in its operative position. By providing a slight clearance between the engaging surfaces of the bead or flanges 25 and its respective chan-

nels or grooves 20, sliding engagement therebetween may be readily accomplished.

It may be here stated that the chute 11, in practice, may be quickly lifted out of its seated position with respect to the U-shaped member 19 should it be desired during the open or business hours of the store.

The lower open end of the chute 11 is provided along its outer side with a reenforcing band or strip 26 to which it is secured in any desired manner. I will now describe in detail the novel means for permitting the passage of a parcel downwardly through the chute but which acts automatically to prevent any unauthorized withdrawal therethrough. This band 26 is provided with a pair of downwardly extending and oppositely disposed lugs or ears 27 for the purpose of pivotally mounting the door 28. A laterally extending rod 29 is secured to the lower side of the door 28 and is located a relatively short distance from the pivotal tub shafts 30.

A gate 31 is pivotally mounted within the chute 11, conveniently located between the upper open end of the chute and the bottom door 28, for example, as illustrated in Figures 1, 2 and 3. This gate 31, which is preferably formed of sheet metal is provided with a pivotal rod 32 to which it is secured and which is adapted to extend through each side wall of the chute 11. The rod 32 is formed into a bell crank shown as at 33 and extends from the same side as does the laterally extending rod 29. A connecting rod 34 is provided with loops upon its extreme ends which are adapted to be engaged by the free end of the bell crank 33 and the laterally extending rod 29 respectively. Cotter pins or other means may be employed for preventing the accidental displacement of the connecting rod with respect to their pivotal connections.

Referring particularly to Figure 2 in the accompanying drawings, it will be noted that the normal position of the gate 31 completely obstructs the passage within the chute, whereas the bottom door is in an open position. The dotted lines in this figure illustrate the other extreme position as, for example, when a package is on its way downward through the chute, whereupon the gate 31, which, in its extremely open position, has lifted the door 28 into its fully closed position through the medium of the connecting rod 24. It will be appreciated that this position is only momentary, because, when the parcel or package has passed clear of the gate 31, the door 28 immediately begins its opening movement.

Obviously, should some unauthorized person insert a stick or other contrivance downwardly through the chute in an effort to extricate or retract a parcel through the chute, the downward movement of the gate 31 will tend to positively close the door 28, thereby foiling any such attempts.

Should it be desired to illuminate the parcel receiving opening to not only render it more attractive during the night but at the same time compel the detection of anyone tampering with this device, I have provided a lighting device 35 at the upper end 24 of the chute 11.

A substantially semi-circular cut-out portion 36 is provided through one of the side flanges 25 for the purpose of receiving the threaded portion of the locking device 13. This locking device consists merely of a knurled headed member having a screw threaded shank portion which is adapted for engagement within the threaded opening formed through one of the legs 21 of the U-shaped member 19.

It will now be appreciated that when it is desired to remove the chute 11 from its seated and locked position, it is merely necessary to unscrew the knurled locking member 13, permitting the lifting of the entire chute through the guideways formed by the grooves 20. The sealing panel 40 may now be downwardly slid into its seated position as is clearly shown in Figure 4 and securely fastened in its proper position by reinserting the locking member 13, as illustrated in Figure 5.

It is to be understood that the invention, however, is not intended to be restricted to the particular construction, nor to the particular applications of such constructions, herein shown and described, nor to the various details thereof, as the same may be modified in various particulars or be applied in many various relations without departing from the spirit and scope of the invention, the practical embodiment herein illustrated and described being merely an attempt to show one of the various possible forms in which the invention might be embodied.

What I claim is:

A parcel receiving device for store fronts having an opening therethrough, comprising a stationary supporting frame located on the inner side of the store front and aligned with said opening, a detachably mounted chute adapted to be held in operative position with respect to said stationary support, a normally closed gate mounted within the chute and adapted to be opened by the downward passage of a parcel therethrough, a movably mounted and normally open door located at the extreme lower end of the chute, and a connecting rod interposed between the gate and said door for causing their simultaneous operation.

HARRY MILLER.
